UNITED STATES PATENT OFFICE.

NATHAN D. POOL AND ANTHIME J. LEVEQUE, OF LEAD, SOUTH DAKOTA.

TILE RACK FOR PLAYING GAMES.

Application filed March 15, 1924. Serial No. 699,473.

To all whom it may concern:

Be it known that we, NATHAN D. POOL and ANTHIME J. LEVEQUE, citizens of the United States, residing at Lead, in the county of Lawrence and State of South Dakota, have invented certain new and useful Improvements in Tile Racks for Playing Games, of which the following is a specification, reference being had to the accompanying drawings.

This invention relates to game apparatus, and particularly to the racks for use in playing Mah-jongg or games using tiles.

In the playing of Mah-jongg, racks are ordinarily used for the reception of the pieces or tiles with which the games are played, these racks being normally angular in form so that the tiles are faced toward the player whose tiles they are and away from the other players. This game is usually played with four players, each of whom must keep before him and exposed to his own view a number of tiles bearing various identifications. Certain of the tiles are required to be exposed as they are played or certain combinations are made and certain other tiles or combinations are concealed but at the end of the game all the tiles in the player's hand are to be exposed.

The general object of the invention is to improve upon the ordinary tile rack by forming the rack of two connected parts, one constituting a channel or rack for the reception of those tiles combinations of which are exposed as they are played, and the other constituting a rack for the "concealed" tiles, that is, tiles which are not exposed until the game is ended, the two racks being so connected together that at the end of the game the rack holding the concealed tiles may be turned over so as to expose the tiles in the player's hand.

My invention is illustrated in the accompanying drawing, wherein:

Figure 1 is a perspective view of a tile rack constructed in accordance with our invention for use in playing Mah-jongg, the tile rack being shown in its playing position;

Figure 2 is a cross section through the tile rack as illustrated in Figure 1;

Figure 3 is a perspective view like Figure 1, but showing the tile rack in its position exposing all of the tiles;

Figure 4 is a cross sectional view as in Figure 2 but showing the tile rack in its tile-exposing position.

Referring to these drawings, it will be seen that this rack consists of two parts 10 and 11. The part 10 is approximately channel-shaped in cross section and has the length of the ordinary rack. The part 10 is formed with the front flange 12 which is higher than the rear flange 13. The part 11 has a relatively high front flange or wall 14, the inner face of which is beveled downward and rearward, and it has a downwardly and forwardly inclined wall 15 and a vertically extending, relatively low rear flange or wall 16.

Attached to the ends of the channeled rack 10 are the metallic strips 17, these strips being longitudinally slotted, as at 18, and projecting from the ends of the member 11 are the trunnions 19. While the game is being played, the parts 10 and 11 are disposed as illustrated in Figure 1 with the wall 14 abutted against the wall 13. The exposed tiles are to be placed in the channeled member or holder 10 face upward so that the players may see them. The "concealed" tiles, however, are to be placed in the member or holder 11 with their backs against the inclined wall 14. When the hand is played out and to be exposed for counting, the rear receptacle is pulled back and then tipped forward, exposing the concealed hand.

With this construction, it will be seen that the two sets of tiles are kept entirely separate, while at the same time they are kept properly assorted and in proper shape, and when the hand is played the hand may be exposed by simply tipping the rear rack without having to take the individual tiles and place them out upon the table face upward or otherwise expose them.

It is to be noted that the front wall 14 of member 11 at its lower end is chamfered or cut away, as at 20, and that the rear wall 13 of the member 10 is extended outward in the form of a flange 21, and when the holder 11 is abutted against the holder 10 this flange 21 fits within the chamfer 20 and thus supports the flange 14 with its inclined face in a horizontal position.

It is to be understood, of course, that while we have particularly designed this

holder for the tiles or pieces used in the game of Mah-jongg, we do not wish to be limited to this as it is obvious that the holder might be used for other playing pieces such as used, for instance, in the game of dominoes or in other games and particularly where it is necessary that certain pieces be concealed and certain pieces are displayed during the playing of the game and then all pieces displayed when the game is at an end.

We do not wish to be limited to any specific material for the construction of these racks or to the details of construction, as it is obvious that the principle of the device might be applied in a number of ways.

We claim:—

1. A tile rack of the character described comprising two separate parallel members, one of said members being formed to provide a longitudinally extending channel for the support of a series of exposed tiles, the other member being disposed at all times behind the first named member and being formed to support a series of tiles with their faces concealed from all but one of the players, the two members being so connected that the last named member may be turned over upon the table substantially at right angles to its normal position to expose the tiles carried therein without affecting the position of the first named member.

2. A tile rack of the character described comprising two parallel tile-holding members, one of said members being approximately channel-shaped, the other of said members having a front wall and a rear wall, the front wall being higher than the rear wall and adapted to conceal the faces of the tiles carried in the holder, strips attached to the ends of the base of one of said holders, each strip being longitudinally slot-

ted, and trunnions slidably and pivotally connecting each end of the other of said holders to said strip, the trunnions passing through the slot of the strip.

3. A tile-holding rack of the character described comprising a channeled member constituting a holder for exposed tiles and having front and rear walls, a second member disposed rearward of the first member and having an upwardly and forwardly extending front wall and a relatively low rear wall, strips attached to the ends of the base of the first named member and extending rearward therefrom, the rear portions of the strip being longitudinally slotted, and trunnions projecting from the ends of the second named member and into said slots whereby the second named member may be shifted into close contiguity with the first member or pulled rearward therefrom and then turned over.

4. A tile rack of the character described comprising a channel-shaped holder for the tiles to be exposed, a channel-shaped holder for the tiles to be concealed, this last named holder having a front wall formed with an inclined rear face, said front wall of the last named holder at its margin being chamfered and the rear wall of the first named holder having an outwardly projecting horizontal flange which, when the two holders are abutted, supports the front wall of the second named holder with its inclined face in a horizontal position, and means connecting the two holders to permit relative sliding and pivotal movement thereof.

In testimony whereof we hereunto affix our signatures.

NATHAN D. POOL
ANTHIME J. LEVEQUE.
